E. M. W. KAEMPFER,
REAR SIGHT FOR FIREARMS.
APPLICATION FILED OCT. 28, 1919.

Patented Oct. 26, 1920.

Inventor:
E. M. W. KAEMPFER

UNITED STATES PATENT OFFICE.

EFFIE MAY WAGNER KAEMPFER, OF LAREDO, TEXAS.

REAR SIGHT FOR FIREARMS.

1,357,095.

Specification of Letters Patent. Patented Oct. 26, 1920.

Application filed October 28, 1919. Serial No. 333,896.

To all whom it may concern:

Be it known that I, EFFIE M. W. KAEMPFER, a citizen of the United States, residing at Laredo, in the county of Webb and State 5 of Texas, have invented certain new and useful Improvements in Rear Sights for Firearms; and I do hereby declare the following to be a full, clear, and exact description of the invention, such as will enable others 10 skilled in the art to which it appertains to make and use the same.

My present invention relates to improvements in sights for firearms, comprising rifles, pistols, shot guns, or other types of 15 guns, or even for ordnance, in which it is desired to provide a luminous auxiliary rear sight to be used at night to enable the marksman to point the piece in the proper direction when the ordinary sights are not 20 visible.

I have shown one embodiment of the invention as applied to the rear sight of a rifle, whereby the rifle may be pointed with facility either by night or day.

25 My invention will be more fully understood after reference to the accompanying drawings, in which like parts are indicated by similar reference symbols throughout the several views, and in which:-

30 Figure 1 is a side elevation of an ordinary service rifle provided with the improved auxiliary rear sight.

Fig. 2 is a side elevation of the ordinary rear sight for use by day, and the auxiliary 35 rear sight for use by night, the parts being on a much larger scale than in Fig. 1, and the auxiliary rear sight being shown in the raised or operative position.

Fig. 3 is a similar view to Fig. 2, except 40 that the housing for the auxiliary rear sight is shown partly in section to expose the parts contained therein, and the pivoted sight block is shown in full lines in the lowered or inoperative position, and in dotted lines in 45 the raised or operative position.

Fig. 4 shows a section along the line 4—4 of Fig. 2, and looking in the direction of the arrows.

Fig. 5 shows a section along the broken 50 line 5—5 of Fig. 2, and looking in the direction of the arrows; and

Fig. 6 is a side elevation on a somewhat larger scale of a slightly modified form of pivoted sight block, parts being broken 55 away.

A represents the barrel of the rifle pro-

vided with the usual front sight B, and with a luminous attachment b, such as is shown in my copending application filed of even date herewith, and entitled Improvements in front sights for firearms, filed October 28, 1919, Serial No. 333,895.

The piece is provided with the usual receiver C carrying the usual or any suitable rear sight D, adapted for ordinary use by 65 day. I do not claim any invention in this ordinary day sight, as I prefer to use my improved attachment in connection with sights of standard types, and I will not further describe the day sight D.

E represents a housing in which the auxiliary sight block and its leaf spring are mounted. This housing may be of built-up structure, but is preferably a single casting brazed or otherwise secured to the receiver 75 C of the piece. This housing is provided with side walls e, one of which is cut away, as at e°, and these two side walls are connected together by the webs e' and e'', slightly spaced apart to permit the passage 80 between the same of the front end of the leaf spring F, which spring is provided with a lug f adapted to abut against the web e'' when the spring is in place, as shown in Fig. 3, and the spring is held in position by a 85 screw bolt G engaging in rear of said lug f, as shown in Fig. 3.

The auxiliary sight block H is pivoted on the screw bolt I, and its rear face h is centrally notched, as shown in Figs. 4 and 5, 90 and on either side of the notch I provide pockets h' in which the luminous compound K, preferably a radium composition, is mounted, as shown most clearly in Fig. 6.

In front of its pivot, the block is provided 95 with a shoulder h⁴ adapted to rest upon the face d of the frame of the usual rear sight D when the auxiliary rear sight is in the raised or operative position, as shown most clearly in Fig. 2.

This block H is provided with an inclined boss h² perforated with a pivot pin, which boss is provided with the toe h³ adapted to engage the leaf spring, and to coact with said spring in holding this block H in either 105 the raised or lowered position as may be desired.

In order to conveniently raise the pivot block H from the lower or closed position to the raised or open position, I provide suitable lifting means, such as a lug h°, shown in Fig. 5, which lug swings down into and 110

projects slightly beyond the curved slot e^o cut in one of the side walls e of the housing E , and this lug may be conveniently engaged by one of the fingers of the marksman and

5 the block may be swung to the open position where it will be held by the leaf spring F .

Instead of providing the lug h^o I may provide a notch or notches, such as h^s , see Fig. 6, in the rear face of the block H , which

10 notch may be engaged either by the thumb nail of the marksman, or it may be engaged by the rim of a cartridge, or by a knife blade, or the like.

It will be noted that the spring F will act 15 upon the heel of the pivot block H in such a way as to hold it in either the raised or lowered position.

When this block is in the lowered position, the pockets h' are closed by the upper face 20 of the web e^2 , as shown in Fig. 3, and thus the luminous compound K in said pockets is protected from dust, dirt, or light.

In carrying the piece on the march, or storing the same away at all times when 25 not desired to use the piece for night firing, this block H is preferably swung down to the closed position, as shown in Fig. 3, and the parts are protected against accidental injury, while when it is desired to use the 30 sight for night firing it is only a matter of a moment to swing the block H to the raised position shown in Figs. 2, 4 and 5. When the gun is properly pointed at night, the luminous front portion b of the front sight 35 will appear midway between the luminous material inclosed in the pockets h' ; the three luminous points then being as indicated in Figs. 4 and 5.

It will be noted that at night it will be 40 ordinarily impracticable to see the object aimed at at long distance, and therefore it will only be necessary under normal conditions to provide for sighting the piece at point blank range, or at a very small elevation 45 only, which can be readily done by the luminous front and rear sight arrangements as herein described and shown.

In order to dismount the parts of the auxiliary rear sight, it will only be necessary to take out the screw bolt I and remove the block H and take out the screw bolt G and remove the leaf spring F . To assemble the parts, reverse the operation.

The housing E is preferably permanently 55 attached to the piece, but it may be detachably connected thereto in any convenient way, if desired.

I have shown one embodiment of the invention which is of simple construction and 60 not likely to get out of order from the rough handling to which firearms are ordinarily subjected when in use; but it will be evident that various modifications might be made in the construction, combination and arrangement of parts which could be used without

departing from the spirit of my invention; and I do not mean to limit the invention to such details except as particularly pointed out in the claims.

It will be obvious also that the herein 70 described auxiliary rear sight may be used on firearms of various kinds, as well as on field guns, or other artillery, or ordnance, and I do not mean to limit the invention to any special type of weapon on which it is 75 used.

Having thus described my invention what I claim and desire to secure by Letters Patent of the United States is:—

1. The combination with a gun, and a 80 sight secured thereto, of an auxiliary sight attachment for the gun comprising a vertically swinging block having a notched arm with pockets therein at each side of said notch, said pockets containing luminous 85 composition, and means for holding said block in the raised or lowered position, relative to the gun.

2. The combination with a gun, and a 90 sight secured thereto, of an auxiliary sight attachment for the gun comprising a vertically swinging block having a notched arm with pockets therein at each side of said notch, said pockets containing luminous 95 composition, and a leaf spring engaging said block and holding the same in the raised or lowered position, relative to the gun.

3. The combination with a gun, of a sight therefor, comprising a housing secured to the gun, a swinging sight block pivoted in 100 said housing, said block having an arm with pockets therein containing luminous material, and automatic means for holding said block in the raised or lowered position, relative to the gun.

4. The combination with a gun, of a sight- 105 ing apparatus therefor comprising a housing secured to the gun, a vertically swinging sight block pivoted in said housing, said block having a notched arm with pockets 110 therein, on each side of said notch, said pockets containing luminous material, and means for holding said block in the raised or lowered position, relative to the gun.

5. The combination with a gun, of a sight- 115 ing apparatus therefor comprising a housing secured to the gun, a vertically swinging sight block pivoted in said housing, said block having a notched arm with pockets 120 therein, on each side of said notch, said pockets containing luminous material, and a leaf spring engaging the heel of said block and holding the block in the raised or lowered position relative to the gun.

6. The combination with a gun, of a sight- 125 ing apparatus therefor comprising a housing carried by the gun and provided with a transverse web, a vertically swinging sight block pivoted in said housing and provided with pockets containing luminous material 130

- adapted to be masked by said web when the auxiliary block is in the lowered position, and automatic means for holding said auxiliary block in the raised or lowered position, 5 relative to the gun.
7. The combination with a gun, of a sighting apparatus therefor comprising a housing carried by the gun and provided with a transverse web, a vertically swinging sight 10 block pivoted in said housing and provided with pockets containing luminous material adapted to be masked by said web when the auxiliary block is in the lowered position, and a leaf spring also mounted in said 15 housing and engaging said block and automatically holding the same in the raised or lowered position, relative to the gun.
8. The combination with a gun, of a sighting apparatus therefor comprising a housing carried by the gun and provided with 20 side walls, one which is slotted, of a swinging sight block pivoted in said housing and provided with pockets containing luminous material, and with a lug registering with the 25 slot in said side wall, and automatic means for holding said block in the raised or lowered position, relative to the gun.
9. The combination with a gun, of a sighting apparatus therefor comprising a housing carried by the gun and provided with 30 side walls, one which is slotted, of a swinging auxiliary sight block pivoted in said housing and provided with pockets containing luminous material, and with a lug registering with the slot in said side wall, and a 35 leaf spring also mounted in said housing and engaging said auxiliary block and automatically holding the same in the raised or lowered position, relative to the gun.
- 40 10. The combination with a gun, of an auxiliary rear sight therefor comprising a housing secured to the gun in rear of the usual rear sight, a swinging sight block pivoted in said housing, said block having an 45 arm with pockets therein containing luminous material, and automatic means for holding said block in the raised or lowered position, relative to the gun.
11. The combination with a gun, of a 50 sighting apparatus therefor comprising a housing secured to the gun, a vertically swinging sight block pivoted in said housing, said block having a notched arm with
- pockets therein, on each side of said notch, said pockets containing luminous material, 55 and means for holding said block in the raised or lowered position, relative to the gun.
12. The combination with a gun, of a sighting apparatus therefor comprising the 60 usual rear sight and rear sight frame carried by the gun, a housing secured to the gun in rear of said sight, a vertically swinging auxiliary sight block pivoted in said housing, said block having a notched arm 65 with pockets therein, on each side of said notch, said pockets containing luminous material, and said block having a shoulder adapted to engage a part of the frame of said rear sight, and a leaf spring engaging 70 the heel of said block and holding the block in the raised or lowered position, relative to the gun.
13. The combination with a gun, of a 75 sighting apparatus therefor comprising the usual rear sight and rear sight frame carried by the gun, a housing carried by the gun in rear of said sight and provided with a transverse web, a vertically swinging sight block pivoted in said housing and provided 80 with pockets containing luminous material adapted to be masked by said web when the auxiliary block is in the lowered position, and said block having a shoulder adapted to engage a part of the frame of said rear sight, and a leaf spring also mounted in said 85 housing and engaging said block and automatically holding the same in the raised or lowered position, relative to the gun.
14. The combination with a gun, of a 90 sighting apparatus therefor comprising the usual rear sight and rear sight frame carried by the gun, a housing carried by the gun in rear of said sight, and provided with side walls, one of which is slotted, a swinging 95 auxiliary sight block pivoted in said housing and provided with pockets containing luminous material, and with a lug registering with the slot in said side wall, and said block having a shoulder adapted to engage 100 a part of the frame of said rear sight, and a leaf spring also mounted in said housing and engaging said auxiliary block and automatically holding the same in the raised or lowered position, relative to the gun.

EFFIE MAY WAGNER KAEMPFER.
